UNITED STATES PATENT OFFICE.

ALFRED INGRAM AND HARRY INGRAM, OF BROOKLYN, NEW YORK, ASSIGNEES TO INGRAMS INCORPORATED, OF BROOKLYN, NEW YORK, A CORPORATION OF NEW YORK.

CLOSURE FOR JARS, BOTTLES, AND OTHER RECEPTACLES.

1,346,653.

Specification of Letters Patent. Patented July 13, 1920.

Application filed October 5, 1917. Serial No. 194,838.

To all whom it may concern:

Be it known that we, ALFRED INGRAM and HARRY INGRAM, citizens of the United States, and residents of Brooklyn, in the county of Kings and State of New York, have invented certain new and useful Improvements in Closures for Jars, Bottles, and other Receptacles, of which the following is a specification.

10 The invention resides more particularly in a novel cap of tin or other suitable metal, with a special compressible gasket in the flange or skirt portion thereof, adapted to the effectual sealing of glass tumblers, jars and other containers. One purpose of the invention is to provide a cap and gasket readily capable of being effectually sealed against plain exterior surfaces of a container, such as a glass tumbler, and another 15 purpose of the invention is to construct such cap and gasket in such manner that when in sealing position they may be conveniently removed from the container.

In carrying out our invention we provide 20 a metal cap adapted to pass downwardly over the upper end of a container and having an encompassing flange or skirt portion which is specially shaped or grooved to receive a packing ring or gasket originally 25 conforming to the shape of the groove, and the said groove and gasket are of such configuration that by pinching together in a vertical direction a projecting annulus constituting a portion of the walls of the 30 groove, the gasket may not only be compressed laterally against the exterior wall of the container but become exposed at its lower edges below the flange or skirt of the cap in convenient position to be engaged by 35 a fork or other implement, by which the gasket may be dislodged or withdrawn to a sufficient extent to permit the removal of the cap without undue exertion or danger 40 of fracturing the container.

45 The invention will be fully understood from the detailed description hereinafter presented, reference being had to the accompanying drawings, in which:

Figure 1 is a side elevation of a glass container sealed with the closure of our invention;

Fig. 2 is a top view of the same;

Fig. 3 is a vertical section, on a larger scale, through a fragmentary portion of the

container and closure, the closure being 55 shown in its normal condition or as when merely applied upon the container without being subjected to the sealing operation, and

Fig. 4 is a like view of the same showing the effect of the sealing operation on 60 the skirt or flange of the cap and on the gasket.

In the drawings, 10 designates a container, which may be a glass tumbler, 11 the cap, 12 a downwardly depending flange or skirt 65 constituting a portion of said cap, 13 an annular beading or groove formed in the lower portion of said flange or skirt, and 14 the gasket disposed within said groove and adapted to engage the exterior wall of 70 the container 10.

The container 10 has plain exterior walls and the cap 11 is adapted to close the upper end of the container and at the upper portion of its flange or skirt 12 snugly encompass 75 the upper outer portions of the container. The groove-portion 13 of the cap is of special formation in that it has a downwardly and outwardly diverging wall 15, a wall 16 extending inwardly and downwardly 80 therefrom, and a lower flange or skirt portion 17 which extends downwardly from the lower edges of said wall 16, all these features being clearly represented in Fig. 3. The lower edge of the annular wall 85 15 and the upper edge of the annular wall 16 meet at an angle, which we number 18. The wall 15 inclines downwardly and outwardly from the upper portion of the flange or skirt 12, and hence starts at a point close 90 to the exterior wall of the container 10. The wall 16 is less in depth than the wall 15, and hence the flange or skirt 17 sets outwardly from the exterior surface of the container 10, leaving a substantial opening 95 between its inner vertical face and the adjacent surface of the container.

The gasket 14 may be of any suitable compressible material, and it has an inner flat face 19 to engage the exterior surface of 100 the container and surfaces 20, 21, 22 fitting against the walls 15, 16, 17 of the cap, the surface 20 diverging downwardly and outwardly, the surface 21 converging downwardly and inwardly and the surface 22 being vertical and against the inner vertical face of the flange 17. The gasket 14 is normally supported within the groove 13 of 105

the flange or skirt 12 when said gasket and the walls of said groove are in their normal condition shown in Fig. 2, and hence the cap and gasket may be assembled and thereafter applied upon the container.

5 The method of sealing the gasket 14 against the container and therefore sealing the container itself is represented in Fig. 4, in which it may be seen that in the sealing 10 operation the angular meeting portions of the walls 15, 16 of the flange 12 are pinched together and in the pinching squeeze the gasket outwardly from the groove 13 and against the exterior wall of the container 15 with a force causing the gasket to very firmly bind against the container and not only seal the same but effectually lock the cap upon the container. The pinching of the adjacent portions of the walls 15, 16 20 together not only forces the gasket material from the groove 13 and against the exterior of the container, but results in the gasket being vertically elongated, reduced in diameter and exposed at its lower portion below 25 the skirt or flange 12, the container thus becoming effectually sealed and the lower edge of the gasket being left in an exposed position where it may be engaged by a fork or other tool and forced downwardly from the 30 cap at such time as it may be desired to remove the cap from the container. The pinching together of the adjacent portions of the walls 15, 16 also results in the flange 17 being drawn upwardly, this also aiding in the 35 exposure of the lower edges of the gasket 14. The gasket 14 is of considerable vertical depth, and hence may engage the exterior plain wall of the container throughout an adequate area and not only afford an effectual seal but securely retain the cap upon 40 the retainer and prevent any accidental displacement of the cap therefrom. The squeezing of the adjacent portions of the walls 15, 16 together, as shown in Fig. 4, also results 45 in the exterior surfaces of the gasket being securely bound against the inner walls of the grooved portion 13 of the flange or skirt 12. The sealing operation may be performed by 50 several simple mechanical expedients, one of which is illustrated in Fig. 4, and involves the employment of dies 23 having a groove 24 adapted to be forced inwardly upon the angle section 18 of the cap and compel the adjacent portions of the walls 15, 16 to come 55 together within the groove 24, thereby compressing the gasket 14 against the container. We will probably form the die in about 60 three sections so as to encompass the cap and effect the moving together of the adjacent portions of the walls 15, 16 in one operation around the entire cap.

On reference to Fig. 4 it may be seen that all of the gasket material in the angular section 18 of the beading 13 of the cap illustrated in Fig. 3, has been squeezed out-

wardly toward the container from the adjacent walls 15, 16, which are squeezed together by the dies 23, and hence the gasket is left in a position in which it may be dislodged downwardly from the cap, and in addition those portions of the gasket which were held within the angular section 18 of the beading 13 are utilized in creating an effectual seal. In Fig. 4 what was the wall 16 of Fig. 3 is numbered 25 and the lower portion of the wall 15 of Fig. 3 and which becomes flattened out in the sealing operation, we number 26 in Fig. 4, and these parts 25, 26 in the closure as transformed in the sealing operation constitute an annular 80 flange 27 of double thickness. It may also be seen on reference to Fig. 4 that the entire structure constituting the beading 13, less the members 25, 26, have, by the sealing operation, been moved inwardly toward the container 10, thereby compressing the gasket over an extended area against the exterior surface of said container.

We call attention to the fact that after the angular section 18 of the beading 13 is in its final condition shown in Fig. 4, the outer wall of the gasket, below the tapered surface 20 thereof, is substantially vertical, and that the beading 13, except for its direct lateral pressure has substantially no influence on the gasket, thus leaving the gasket vertically elongated in a downwardly direction without being held in any undercut or lateral cavity of the beading, all this being quite essential, because we desire to secure 100 an extended sealing zone below the plain upper portion of the flange 12 which engages the outer walls of the container and also desire to provide a seal wherein the gasket may be removed by being pulled downwardly from the portion of the cap engaging the same. In this case the inner wall of the gasket engages the plain wall of the receptacle and the outer wall of the gasket is against surfaces which do not require the 110 tearing or mutilation of the gasket in withdrawing the same therefrom, the gasket being in no substantial undercut or lateral recess of the cap. In addition the sealing of the container results in the gasket not only 115 being compressed laterally, but extended vertically in a downwardly direction and in being exposed below the cap so that it may be properly and conveniently removed with the use of a fork or other convenient tool. 120 We are quite well aware that it is not new to compress a gasket against the side of a container or below a shoulder formed on the container, but we have no knowledge that anyone preceding ourselves have produced 125 a seal possessing the characteristics of the invention sought to be protected herein.

What we claim as our invention and desire to secure by Letters-Patent, is:

1. A closure for a receptacle comprising a 130

cap having an annular depending flange or skirt portion to encompass the upper exterior walls of the receptacle, and a gasket within said flange or skirt portion, said 5 skirt portion initially having a downwardly and outwardly diverging annular wall, a wall converging downwardly and inwardly from the outer edges of said first mentioned wall and a flange extending downwardly 10 from the inner edge of said second wall, and said gasket being adapted on one face to engage the exterior wall of the receptacle and, initially, at its outer face said walls at their adjacent angular portions and lower 15 flange, and said walls being adapted to be squeezed toward each other for forcing said gasket therefrom and against the plain exterior wall of the receptacle.

2. A closure for a receptacle comprising a 20 cap having an annular depending skirt or flange to encompass the upper exterior walls of the receptacle, and a gasket within said skirt portion, said skirt initially having below its upper portion a downwardly and 25 outwardly diverging annular wall, a wall converging downwardly and inwardly from the outer edges thereof and a flange extending downwardly from the inner edge of said second wall and set outwardly from the wall 30 of the receptacle, and said gasket being adapted at its inner face to engage the exterior wall of the receptacle and at its outer face said walls and lower flange of said skirt, and the adjoining angular portions of the 35 walls of said skirt portion being adapted to be squeezed together so as to force the gasket therefrom and against the exterior surface of said receptacle and expose a portion of the gasket below said lower flange, the gasket 40 then being substantially free of any lateral recess in the flange of the cap and being capable of being pulled downwardly from its sealing position.

3. In combination with a receptacle having 45 plain exterior surfaces, a closure of the character described therefor comprising a cap having a depending skirt to encompass the exterior surfaces of said receptacle at the upper end thereof and formed with an 50 upper plain portion and a lower beaded portion, and a gasket held within said lower beaded portion, said beaded portion initially comprising upper and lower walls and a depending flange set outwardly from the surface of said receptacle, said gasket at its 55 inner face being adapted to engage the exterior surface of the receptacle and at its outer face said beaded portion of said skirt, and said beaded portion of said skirt having 60 adjacent annular portions squeezed together

to force the gasket from said portions and move said beading toward the container, compressing the gasket against the container and exposing the lower edges of the gasket below said skirt, the gasket being 65 thereby elongated vertically in a downwardly direction and being substantially free of any lateral recess in the flange of the cap tending to prevent the gasket from being pulled downwardly from its sealing position. 70

4. In combination with a receptacle having plain exterior walls, a closure of the character described therefor comprising a cap having a depending flange or skirt portion 75 adapted to encompass the exterior surfaces of the receptacle at the upper end thereof and formed with an upper plain section and a lower beaded section comprising upper and lower walls and a flange set 80 outwardly from said receptacle and extending downwardly from the inner edge of said lower wall, and a gasket in said beaded section, said beaded section being in the condition of having a portion of its said walls 85 bent toward and against each other against the resistance of said gasket and holding said gasket squeezed therefrom and vertically elongated in a downwardly direction and compressed against the plain walls of 90 the receptacle.

5. In combination with a receptacle having plain exterior walls, a closure of the character described therefor comprising a cap having a depending flange or skirt portion 95 adapted to encompass the exterior surfaces of the receptacle at the upper end thereof and formed with an upper plain section and a lower beaded section comprising upper and lower walls of unequal length 100 and a flange set outwardly from said receptacle and extending downwardly from the inner edge of said lower wall, which is shorter than said upper wall, and a gasket in said beaded section, said beaded section 105 being in the condition of having a portion of its said walls bent toward and against each other against the resistance of said gasket and holding said gasket squeezed therefrom vertically elongated in a downwardly direction and compressed against the plain walls of the receptacle. 110

Signed at New York city, in the county of New York and State of New York, this 27th day of September, A. D. 1917.
